(57) **CLAIM**

The ornamental design for an ear thermometer, as shown and described.

DESCRIPTION

FIG. 1 is a perspective view of an ear thermometer showing the new design;

FIG. 2 is a top plan view thereof;

FIG. 3 is a bottom plan view thereof;

FIG. 4 is a back elevational view thereof;

FIG. 5 is a side elevational view thereof, the opposite side elevational view being a mirror image of FIG. 5; and,

FIG. 6 is a front elevational view thereof.

The broken line showing is for illustrative purposes only and forms no part of the claimed design.
